United States Patent Office

Des. 196,560
Patented Oct. 15, 1963

196,560

COMBINED BRUSH AND COMB OR THE LIKE

Eric Dent, 21 Dale Ave., Toronto, Ontario, Canada

Filed June 12, 1961, Ser. No. 65,550

Term of patent 14 years

(Cl. D9—2)

Fig. 1.

Fig. 2.

Fig. 3.

Fig. 4.

Fig. 5.

FIG. 1 is a perspective view of the combined brush and comb;

FIG. 2 is a side view thereof;

FIG. 3 is a bottom view of the same;

FIG. 4 is a top view of the combined brush and comb; and

FIG. 5 is an enlarged view of the portion of the view shown in FIG. 3 which appears between lines A and B. I claim:

The ornamental design for a combined brush and comb or the like, as shown.
